UNITED STATES PATENT OFFICE.

MAX LEONARD TOWER, OF MIDDLEPORT, NEW YORK, ASSIGNOR TO NIAGARA SPRAYER CO., OF MIDDLEPORT, NEW YORK, A CORPORATION OF NEW YORK.

INSECTICIDE.

1,416,526.

Specification of Letters Patent. Patented May 16, 1922.

No Drawing.

Application filed September 15, 1919. Serial No. 323,772.

To all whom it may concern:

Be it known that I, MAX L. TOWER, a citizen of the United States, and a resident of Middleport, in the county of Niagara and

5 State of New York, have invented a new and useful Insecticide, of which the following is a full, clear, and exact description.

This invention relates to insecticides and has for an object to provide an improved

10 compound especially efficacious for the destruction of sucking insects, as for instance aphis, pear psylla and red bug.

A further object is to provide an insecticide which may be a dust mixture for certain insects, or may contain an ingredient which is a stomach poison for chewing insects.

In producing the compound the percentage of each ingredient may be varied to 20 quite a large extent so long as enough plaster of Paris is introduced to combine with the water of the nicotine solution.

Briefly the composition consists of a nicotine compound in the form of a dust produced by mixing a strong nicotine solution with an inert powder or filler and a dehydrating agent. Preferably the mass or base in which to provide or suspend the nicotine compound consists of finely ground sulphur 30 or sublimed sulphur because it has a decided fungicidal value. The dehydrating agent is preferably plaster of Paris because of its cheapness and is a ready combination with the nicotine solution. The mass is made 35 light and fluffy large volume per unit weight by means of a filler, which may be a number of different substances, as for instance wood flour, talc, tobacco dust, or other light fluffy powder. The tobacco dust is preferable because it is very light and fluffy, and also because it contains a small percentage of nicotine and this merely adds to the nicotine contents of the solution, which is dehydrated by means of the plaster of Paris.

40 A forty per cent solution of nicotine sulphate is preferable as a source of the nicotine contents of the mixture because of its high initial nicotine content, and because the sulphate of nicotine is more stable than the 45 alkaloid or any other of its common salts.

Where the compound is to be used in killing chewing insects, as for instance the larva of the codling moth, a suitable internal poison is added, as for instance calcium arsenate.

55

The ingredients as recited may have the proportions varied widely while presenting an extremely fluffy dusty mixture for the purpose desired.

The following formulas are typical compounds, though other proportions may be used:

(A)	77 $\frac{1}{2}$	parts fine sulphur.	
	16	parts tobacco dust.	65
	5	parts plaster of Paris.	
	2 $\frac{1}{2}$	parts 40% nicotine sulphate solution.	
(B)	67 $\frac{1}{2}$	parts fine sulphur.	
	15	parts tobacco dust.	70
	10	parts lead arsenate.	
	5	parts plaster of Paris.	
	2 $\frac{1}{2}$	parts of 40% nicotine sulphate solution.	
(C)	66 $\frac{1}{2}$	parts fine sulphur.	75
	1	part soluble sulphur.	
	15	parts tobacco dust.	
	10	parts calcium arsenate.	
	5	parts plaster of Paris.	
	2 $\frac{1}{2}$	parts of 40% nicotine sulphate solution.	80

In compounding or mixing any particular batch above indicated, or any variation thereof, the parts are intermingled and ground by any suitable means, as for instance by a ball mill, first grinding together the sulphur, tobacco dust, plaster of Paris and in formulas B and C, the arsenate, then adding the nicotine sulphate solution and finally grinding the mixture a sufficient length of time to produce a fine, dry, dusty mass.

What I claim is:

1. An insecticide comprising a nicotine salt solution, a dehydrating agent, fine sulphur acting as a base in which the nicotine salts and the dehydrating agent are suspended and an arsenate. 95

2. An insecticide comprising in substantially the proportions given, a forty per cent nicotine sulphate solution, plaster of Paris, tobacco dust, finely divided sulphur and an arsenate. 100

3. An insecticide in the form of dust comprising a nicotine sulphate solution, finely divided sulphur, plaster of Paris, sufficient to dehydrate the nicotine sulphate solution and lead arsenate. 105

4. An insecticide in the form of powder comprising a substantially forty per cent 110

- nicotine sulphate solution, plaster of Paris, sufficient to dehydrate said solution, lead arsenate, tobacco dust, and finely divided sulphur.
5. An insecticide in the form of dust comprising a forty per cent nicotine sulphate solution two and one half parts, plaster of Paris five parts, lead arsenate ten parts, tobacco dust fifteen parts, and finely divided sulphur sixty seven and one half parts.
6. An insecticide in the form of dust comprising a nicotine sulphate solution, finely divided sulphur, plaster of Paris sufficient to dehydrate said solution, and an arsenate.
7. An insecticide in the form of dust comprising a substantially forty per cent nicotine sulphate solution, a dehydrating agent sufficient to dehydrate said solution, a metallic arsenate, tobacco dust and finely divided sulphur. 15

MAX LEONARD TOWER.
